US0D1033403S

(12) **United States Design Patent** (10) **Patent No.:** **US D1,033,403 S**
(45) **Date of Patent:** **** Jul. 2, 2024**

(54) **WIRELESS MICROPHONE WITH A COVER**

(71) Applicant: **Logitech Europe S.A.**, Lausanne (CH)

(72) Inventors: **James Leigh Toggweiler**, Oakland, CA (US); **Steven Ryutaro Takayama**, Menlo Park, CA (US); **Anthony Cooper Mattana**, Chicago, IL (US); **Mark Harold Burleson**, Thousand Oaks, CA (US); **Adam Kirk Bennett**, Ventura, CA (US); **Aron Michael Rosenberg**, Lafayette, CA (US)

(73) Assignee: **LOGITECH EUROPE S.A.**, Lausanne (CH)

(**) Term: **15 Years**

(21) Appl. No.: **29/813,981**

(22) Filed: **Nov. 2, 2021**

(51) **LOC (14) Cl.** **14-01**

(57) **CLAIM**

The ornamental design for a wireless microphone with a cover, as shown and described.

DESCRIPTION

FIG. 1 is a top back left side perspective view of a wireless microphone with a cover according to our design;

FIG. 2 is a bottom front left side perspective view of the wireless microphone with a cover;

FIG. 3 is a back elevation view of the wireless microphone with a cover;

FIG. 4 is a left side elevation view of the wireless microphone with a cover;

FIG. 5 is a front elevation view of the wireless microphone with a cover;

FIG. 6 is a right side elevation view of the wireless microphone with a cover;

FIG. 7 is a top plan view of the wireless microphone with a cover; and,

FIG. 8 is a bottom plan view of the wireless microphone with a cover.

The dashed lines shown in the figures depict portions of the wireless microphone with a cover that form no part of the claimed design.

1 Claim, 8 Drawing Sheets
